BOWLING BALL RETARDER

Otto Schlafender, Muskegon, Mich., assignor to
The Brunswick-Balke-Collender Company

Application September 1, 1950, Serial No. 182,822

11 Claims. (Cl. 273—47)

1

This invention relates generally to a device for retarding bowling balls and more particularly to a ball retarder adapted to be located adjacent the ball entrance to a rack in order to retard bowling balls as they are returned to the rack and permit them to roll on to the rack at a greatly reduced speed.

It is the general object of the invention to provide a new and improved bowling ball retarder. More particularly it is the object of the invention to provide a ball retarder of simple construction which is efficient in operation and easy to maintain.

It is another object of the invention to provide a bowling ball retarder having a rockable device or cradle pivotally supported between the downwardly inclined portion of the tracks of a ball rack and having means normally located in the path of the ball so as to engage a ball, a latch device retaining said cradle in its ball engaging position and adapted to permit the ball engaging portion of the cradle to yield slightly when initially engaged by a ball, said latch device being released during such initial movement of the cradle to permit the cradle to rock and enable a ball to roll over the cradle and down the inclined portion of the tracks by the action of gravity, and means operable after the passage of a ball over the cradle to reset the cradle and latch device and condition them for retarding another ball.

Other objects and advantages will become readily apparent from the following detailed description taken in connection with the accompanying drawings:

Fig. 1 is a fragmentary side elevation of a bowling ball retarder embodying the invention installed on the downwardly inclined portion of the tracks of a ball rack.

Fig. 1a is an enlarged fragmentary view of the lower portion of the retarder of Fig. 1.

Fig. 2 is an end elevation looking at the right-hand end of Fig. 1.

Fig. 3 is a fragmentary side elevation of a modified form of the invention along the line 3—3 of Fig. 4.

Fig. 3a is a fragmentary section along the line 3a—3a of Fig. 3.

Fig. 3b is an enlarged fragmentary section along line 3b—3b of Fig. 3.

Fig. 4 is an end view looking at the right-hand end of Fig. 3.

While the invention is herein disclosed in its preferred form and also in a modified form, it is not intended to limit the invention to the par-

2

ticular forms shown, it being contemplated that various changes may be made by those skilled in the art without departing from the spirit and scope of the appended claims.

As shown in Figs. 1, 1a and 2, the invention is installed on a ball rack having a pair of parallel tracks 10, a portion of which are downwardly inclined at 11, balls being returned to the rack normally passing from left to right up over an inclined portion 12 and downwardly over portion 11. A cradle member 13, somewhat in the form of a bellcrank, is located between the tracks 10 and is rockably mounted thereon by means of a horizontally extending pivot pin 14.

15 A roller 15, preferably of rubber or other resilient material, is rotatably mounted on the upper end of the cradle by means of a shaft 16 and is normally in the position shown in full lines in Fig. 1 wherein it will engage a ball B 20 rolling down inclined portion 11 of the tracks 10. The cradle member has a slightly inclined bottom surface 17 which joins (adjacent the right-hand end of the cradle member as shown in Fig. 1) with a surface 18 rising at a slightly 25 greater angle to the horizontal. The front or left-hand end 19 of the cradle member normally lies below the path of a ball as it rolls down the inclined portion 11 of the tracks.

The cradle member is normally held in its ball 30 engaging position by means of a latch device herein shown as comprising a lever 20 pivotally supported on a pin 21 extending between a pair of brackets 22, 23 secured to the tracks 10 as by means of bolts 24. The shorter end of the 35 lever 20 extends upwardly and preferably carries a roller 25 which may also be of rubber or of other resilient material. The lever 20 as shown consists of a pair of laterally spaced and parallel members 26 between which the roller is 40 rotatably supported on a pin 27. The lower ends of the lever members 26 are provided with slots 28 which extend inwardly from the rear or right-hand edge as shown in Fig. 1 at 29 and then upwardly as shown at 30. The brackets 22 and 45 23 have slots at 31 formed therein (as shown best in Fig. 1a) consisting of a portion 32 concentric with the pin 21 and a portion 33 extending downwardly therefrom. A pin 34 extends freely through the slots 31 and also through 50 the slots 28 in the bracket members 22, 23 and has a cotter pin 35 or other device at each outer end arranged to retain the pin in the slots. The pin is free to move from one end to the other end of the slots 31 for a purpose hereinafter more 55 fully described.

When the cradle 13 and latch member 20 are in their normal positions indicated at *a* in Fig. 1, the roller 25 engages against the surface 17 of the cradle immediately adjacent the point where the surface 17 joins the surface 18. At that time the pin 34 is at the extreme right-hand end of the slot portion 32 (as indicated at *a* in Fig. 1a) and also extends through the slot portion 30 of the latch member. Upon engagement with the cradle roller 15 by a ball B the cradle member is rocked slightly in a clockwise direction (Fig. 1) from the full line position *a* to the dotted line position *b*. The latch member 20 is then swung in a clockwise direction from its normal position *a* to the dotted line position *b*, the roller 25 then engaging the inclined surface 18 on the cradle member. During this movement the pin 34 has moved along the portion 32 of the slot 31 in the bracket members to the position *b* of Fig. 1a and is then in a position to drop by gravity along the portion 33 of the slot 31. The weight of the ball B (which is still on the inclined portion 11 of the tracks after it has been stopped) exerts a force on the roller 15 operative to rock the cradle member from the dotted line position *b* to the dashed line position *c*. This movement of the cradle member is permitted as the pin 34 moves downwardly in the slot portion 33 and at the same time moves downwardly in the slot 28 of the latch member until the latch member is disengaged from the pin and swings out to the adjacent dashed line position *c*. When the cradle member reaches its position *c* the ball has rolled over the cradle 13 and its roller 15 and down to the horizontal portion of the tracks 10.

During the passage of the ball over the cradle member the front end 19 thereof extends upwardly as shown in Fig. 1 in position to block a second ball if one should inadvertently arrive at the ball retarder before the cradle member returns to its normal position.

The front end of the cradle member is preferably weighted with a weight member 40, if necessary, to enable the cradle member to return to its normal position by gravity. During the return of the cradle member the latch member 20 is permitted to swing in a counterclockwise direction from its position *c* whereupon the open end of the portion 29 of slot 28 receives the pin 34 which is then in the position *c* of Fig. 1a at the lower end of the portion 33 of the slot 31. Further swinging movement of the latch member enables the upwardly inclined portion of the slot 28 to elevate the pin 35 into the portion 32 of the slot 31 and this enables the pin to move back to the right-hand end of the slot portion 32 to position *a*.

A stop member 41 is preferably provided between the tracks to limit the counterclockwise movement of the cradle member and to determine its normal position. Another stop member 42 is carried on the brackets 22, 23 to engage the surface 18 of the cradle member and limit its clockwise movement when it moves into position *c* enabling the ball to pass through the retarder.

In the form shown in Figs. 3 and 4 a cradle member 50 is rockably supported on a shaft 51 extending between the inclined portions 11 of the tracks 10. A ball engaging roller 52 is rotatably mounted on the upper end of a lever 53 which is pivotally supported in a slot 50' in the front or left-hand end of the cradle member 50, by a pin 54, as shown in Figs. 3 and 3b. The lower and longer end 55 of the lever 53 extends downwardly through a U-shaped bracket 56 which is secured

to the underside of the tracks by bolts 57. The lower end of the lever 53 has a cut out portion 58 providing a surface 59 which normally rests on the lower wall 60 of the bracket 56, the extending portion 61 of the lever then projecting through the rear or right-hand end of a slot 62 in bracket wall 60.

When the roller 52 is engaged by a ball B rolling down the inclined portion 11 of the tracks 10, the impact swings the lever 53 from the full line position *a* of Fig. 3 to the dot-dash line position *b*, this swinging movement of the lever being permitted by the length of the slot 62. When the left end surface of the projecting portion 61 engages the left-hand end 63 of the slot 62, the entire lever is free to move downward in the slot, as the width of the lower portion 55 of the lever is less than the corresponding dimension of the slot 62 (see Fig. 3a). The weight of the lever and cradle is then sufficient to swing the cradle in a counterclockwise direction to the dotted line position indicated at *c* in Fig. 3, the lever then passing downwardly through the slot 62 to its position *c*. As the roller 52 then moves to its dotted line position marked *c* the ball B is free to roll down the inclined portion of the tracks which extends above the left-hand end of the cradle. As the ball engages a bumper 64 of rubber or other resilient material, on the right-hand end of the cradle member, it operates to swing the cradle in a clockwise direction about the shaft 51. This movement of the cradle member pulls the lever 53 upwardly through the slot 62 until the surface 59 on the lever rises slightly above the lower wall 60 of the bracket, and the lever then swings back into its *a* position.

A stop member 65 is preferably provided on the bracket 56 to engage the end surface of the cradle member to determine the normal position of the cradle member. As the lower end of the lever returns to its *a* position it latches the cradle in its normal position and conditions the device for retarding another ball.

As shown in the drawings a stop pin 66 is located in the forward portion of the bracket 56 and has a resilient sleeve 67 thereon which engages the lower portion 55 of the lever as it swings to its *b* position on engagement of a ball with roller 52, thus stopping the swinging movement of the lever and cushioning the impact of the ball.

I claim:

1. A bowling ball retarder having, in combination with a pair of declining ball tracks, a rockable stop member located between said tracks and journaled on a horizontal axis transverse of the ball tracks, and normally positioned with its trailing end up, a rubber roller on said trailing end in position to engage a ball rolling down the tracks, a frame located below the tracks and carrying a horizontal pivot pin, a lever pivoted on said pin and normally extending somewhat vertically, a resilient roller journaled on the upper end of said lever and normally underlying the trailing end of said rockable stop member; said lever having a slot in its lower end extending inwardly and upwardly from its rear edge, said frame having plate-like portions one on each side of said lever and provided with coinciding slots a portion of which are concentric with the lever pivot and on a level with the top of the arcuate slot of the lever and joining portions of which slots extend downwardly and forwardly therefrom to a position on a level with the open end of the lever slot, a pin freely contained in the frame-plate slots and in

the lever slot when the lever is in its member engaging position, said pin shifting through said concentric portion of the plate slots when a ball engages said roller and thereafter dropping downwardly in said slots and freeing itself from the lever slot as the ball rocks the stop member farther and passes through the retarder.

2. A bowling ball retarder having, in combination with a pair of declining ball tracks, a rockable stop member located between said tracks and journaled on a horizontal axis transverse of the ball tracks, and normally positioned with its trailing end up, a rubber member on said trailing end in position to engage a ball rolling down the tracks, a frame located below the tracks and carrying a horizontal pivot pin, a lever pivoted on said pin and normally extending somewhat vertically with its upper end underlying the trailing end of said rockable stop member, said lever having a slot in its lower end extending inwardly and upwardly from its rear edge, said frame having a plate-like portion on one side of said lever and provided with a slot, a portion of which is concentric with the lever pivot and on a level with the top of the slot of the lever and joining portions of which slot extend downwardly and forwardly therefrom to a position on a level with the open end of the lever slot, a pin freely contained in the frame-plate slot and in the lever slot when the lever is in its member engaging position, said pin shifting through said concentric portion of the plate slot when a ball engages said rubber member and thereafter dropping downwardly in said slots and freeing itself from the lever slot as the ball rocks the stop member farther and passes through the retarder.

3. A bowling ball retarder as defined in claim 2 having means to swing the rockable stop member back to its normal position after the passage of a ball therethrough and to re-engage said last mentioned pin in said lever slot.

4. A stop for bowling balls, comprising, in combination with a ball return track, a cradle swingably mounted on said return track and having when in ball receiving position a rearwardly and upwardly extending portion having a roller rotatably mounted in its upper end, said cradle when in ball receiving position having a forwardly extending portion positioned below the ways of the return track, means for retaining the cradle in ball receiving position, means for stopping a ball when it enters the cradle and strikes said roller comprising a lever pivotally supported on a horizontal axis below the cradle axis and having a shorter upper end carrying a roller engageable with the straight and forwardly-downwardly inclined bottom edge of the cradle, a stop device engaging the lever and permitting the lever to swing a short distance in a direction permitting the ball to rock the cradle slightly when the ball engages said roller, and means supporting said stop device permitting the device to fall by gravity to a non-stop lever disengaged position and enable the weight of the ball to rock the cradle sufficiently to roll the ball over said roller end thereof, said cradle rocking back to its ball receiving position after passage of the ball, and means on the lever operable to reset said stop device in its stop position as the lever swings back to its normal cradle engaging position.

5. A stop for bowling balls, comprising in combination with a ball return track, a cradle swingably mounted on said return track and having

when in ball receiving position an upwardly extending portion positioned in the path of a ball on the track, a means for retaining the cradle in ball receiving position, means for stopping a ball when it strikes the cradle comprising a lever pivotally supported on a horizontal axis below the cradle axis and having an upper end engageable with a bottom portion of the cradle, a stop device engaging the lever and permitting the lever to swing a short distance in a direction permitting the ball to rock the cradle slightly when the ball engages the cradle, and means supporting said stop device permitting the device to move to a non-stop lever disengaged position after said short swing of the lever and enable the weight of the ball to rock the cradle sufficiently to roll the ball over the cradle, said cradle rocking back to its ball receiving position after passage of the ball, and means on the lever operable to engage and reset said stop device in its stop position as the lever swings back to its normal cradle engaging position.

6. A stop for bowling balls, comprising, in combination with a ball return track, a cradle swingably mounted on said return track and having when in ball receiving position a portion extending upwardly into the path of a ball, means for retaining the cradle in ball engaging position, means for stopping a ball when it strikes the cradle comprising a lever pivotally supported on a horizontal axis and having one end normally engaged with the cradle, a stop device engaging the lever and permitting the lever to swing a short distance in a direction permitting the ball to rock the cradle slightly when the ball engages the cradle, and means supporting said stop device when the lever is in its cradle engaging position and permitting the device to move to a non-stop lever disengaged position after the lever has swung such short distance and enable the weight of the ball to rock the cradle sufficiently to roll the ball over said cradle.

7. A bowling ball retarder comprising in combination with ball return tracks, a cradle rockably supported between said tracks and movable from a position wherein a part of the cradle projects into the path of a ball to a position enabling the ball to roll over said part of the cradle, means for retaining the cradle in ball engaging position including a latch member, means engaging said latch member for controlling limited movement of said member from its normal position to a position it enters upon the impact of a ball with the cradle, said controlling means disengaging from the latch member to permit extended movement thereof while the ball rolls over the cradle member, and means for resetting the cradle member and latch member.

8. A bowling ball retarder comprising in combination with ball return tracks, a member rockably supported on said tracks and movable from a position wherein a part of the member projects into the path of a ball to a position enabling the ball to roll over said part of the member, means for normally retaining said member in ball engaging position including a latch device, means engaging said latch device for controlling limited movement of said device from its normal position to a position it enters upon an impact of a ball with said rockable member, said controlling means disengaging from the latch device to permit extended movement thereof while the ball rolls over the rockable member, and means for resetting the rockable member and latch device.

9. A bowling ball retarder comprising, in com-

bination with downwardly sloping ball return tracks, a cradle pivotally supported on said tracks, a lever operable normally to hold the cradle in its ball retarding position, a positive stop device permitting the lever to swing slightly when a ball is retarded by the cradle, means operable by the lever when said lever is swung slightly to render the stop device ineffective and permit the ball to roll down over the cradle and means for restoring the lever to its cradle supporting position and rendering the stop device effective as the cradle swings back to its normal ball retarding position.

10. A bowling ball retarder comprising, in combination with downwardly sloping ball return tracks, a cradle pivotally supported between said tracks, a pivotally supported lever operable normally to maintain or hold the cradle in its ball retarding position, a positive stop device permitting the lever to swing a limited amount when a ball is stopped, means operable by the lever when said lever is swung such amount to render the stop device ineffective and permit the lever to swing to a position enabling a ball to roll down the tracks and over the cradle and means for automatically restoring the cradle to its ball retarding position upon release of a ball therefrom.

11. A bowling ball retarder comprising, in combination with downwardly sloping ball return tracks, a cradle pivotally supported approximately at its mid-point between said tracks and having ball-retarding and ball-blocking portions, a pivotally supported lever having one end in engagement with said cradle, a stop device having lever-engaging and non-engaging positions, means supporting said stop device for slight movement in said first position when a ball rolls onto said cradle and initially shifts the lever, said supporting means allowing the stop device to move to its non-engaging position after said slight movement which permits the lever to move further as the cradle moves about its pivot to lower said ball-retarding portion and raise the ball-blocking portion.
